UNITED STATES PATENT OFFICE.

HELEN M. ANDALORO, OF PITTSTON, PENNSYLVANIA.

HAIR CRIMPER.

Application filed December 27, 1923. Serial No. 683,013.

To all whom it may concern:

Be it known that I, HELEN M. ANDALORO, a citizen of the United States, residing at Pittston, in the county of Luzerne and State 5 of Pennsylvania, have invented certain new and useful Improvements in Hair Crimpers; and I do hereby declare the following to be a full, clear, and exact description of the invention, such as will enable others 10 skilled in the art to which it appertains to make and use the same.

The invention relates to means whereby the hair may be crimped or waved in order to produce a pleasing effect, the device being light, simple and effective and adapted 15 to be worn without inconvenience, discomfort or producing an untidy appearance.

Other objects and advantages will be apparent and suggest themselves as the nature 20 of the invention is understood.

While the drawings illustrate an embodiment of the invention it is to be understood that in adapting the same to meet different conditions and requirements, various 25 changes in the form, proportion and minor details of construction may be resorted to without departing from the spirit of the invention.

Referring to the accompanying drawings 30 forming a part of the application:

Figure 1 is a side view of the device showing the same applied,

Figure 2 is a front view, and

Figure 3 is a diagrammatic view, the outer ends of the crimping elements being broken away.

Corresponding and like parts are referred to in the following description and designated in the several views of the drawings 40 by like reference characters.

The device comprises a head strap 1 and a plurality of crimping elements 2, the several parts 1 and 2 preferably consisting of elastic straps, the strap 1 being broad and stout, whereas the straps 2 are narrow and light. The head strap 1 is reinforced at its ends, as indicated at 3, this being accomplished by folding end portions of the strap and stitching the same. A clasp 4 is provided at one end of the head strap 1 and is

adapted to secure the crimping elements 2 in the required adjusted position.

The crimping elements 2 are attached at one end to a reinforced end of the head strap 1 and diverge and are adapted to be adjustably connected to the opposite end of the head strap 1 by means of the clasp 4. This is shown most clearly in Figure 1.

In practice, the hair is preferably dressed in pompadour and gathered at the back in a Psyche knot, after which the device is placed in position by engaging the strap about the back of the head below the Psyche knot and passing the strap 2 over the head so as to engage the hair at different points. The loose ends of the straps 2 are engaged with the clasp 4 and said straps are drawn so as to compress the hair whereby to produce the crimp or Marcel wave effect. Obviously the hair may be dampened and the device worn until the crimp or wave effect is produced, after which the device is removed.

What is claimed is:

1. A hair crimper comprising a head strap, a clasp at one end of the strap, and a plurality of crimping straps attached at one end to the opposite end of the head strap and adapted to be brought together and adjustably connected to the opposite end of the strap by means of the clasp. 75

2. A hair crimper comprising a head strap, a clasp at one end of the strap, and a plurality of crimping straps attached at one end to the opposite end of the head strap and adapted to be brought together and adjustably connected to the opposite end of the strap by means of the clasp, the head strap being reinforced at opposite ends and the crimping straps having a divergent relation, 85 and the several straps being elastic, the head strap being relatively broad and stout and the crimping straps light and narrow. 90

In testimony wherof I affix my signature in presence of two witnesses.

HELEN M. ANDALORO.

Witnesses:

V. MINNELLI,

ROSE ANDALORO.
